UNITED STATES PATENT OFFICE.

GAIL E. PLUNKETT, OF NEW RICHMOND, INDIANA.

DESIGN FOR AN ENVELOP-BLANK.

SPECIFICATION forming part of Design No. 29,079, dated July 19, 1898.

Application filed December 19, 1896. Serial No. 616,346. Term of patent 14 years.

To all whom it may concern:

Be it known that I, GAIL E. PLUNKETT, a citizen of the United States, residing at New Richmond, in the county of Montgomery and 5 State of Indiana, have invented and produced a certain new and original Design for Envelop-Blanks; and I do declare the following to be a full, clear, and exact description of the invention, such as will enable others skilled 10 in the art to which it appertains to make and use the same.

The invention relates to a new and original design for an envelop-blank; and it consists 15 of a blank of the shape and configuration shown in the accompanying drawing, in which I have illustrated the invention in plan view.

The leading feature of the design consists 20 of the rectangular body portion 1, the end flap 2, of a width and length corresponding to the area of the body portion 1, the end flap 25 5, of a length less than that of the body portion 1 and for a distance of a width corresponding to that of the body portion 1, thence formed with tapering sides 7, of less width than the body portion 1 and terminating in 25 a straight edge 8 at an obtuse angle to the sides 7 and provided with a flat truncated conical head 10, having the neck 9, the wings 12 at the side edges of the body portion 1, said wings formed with straight edges 14 and 30 tapering base edges 13 and with truncated conical heads 16, connected to the straight edges by necks 17, and said flap 2 having parallel vertically-disposed slits 3 and the slit 4, extending at right angles to the slits 3, and 35 said slits 3 and 4 being arranged in triangular order.

What I claim is—

The design for an envelop-blank as herein 40 shown and described.

In testimony whereof I hereunto affix my signature in presence of two witnesses.

GAIL E. PLUNKETT.
